UNITED STATES PATENT OFFICE.

GOTTLOR WARTTINGER, OF BERLIN, GERMANY.

PORTABLE DUMPING APPARATUS.

SPECIFICATION forming part of Letters Patent No. 360,260, dated March 29, 1887.

Application filed April 15, 1886. Serial No. 198,919. (No model.) Patented in England March 26, 1886, No. 4,298; in Belgium April 15, 1886, No. 72,558; in Italy May 4, 1886, No. 19,766/148; in Spain July 26, 1886, No. 8,930; in France July 30, 1886, No. 175,189; in Austria-Hungary August 12, 1886, No. 12,614 and No. 38,472, and in Germany December 2, 1886, No. 38,613.

To all whom it may concern.

Be it known that I, GOTTLOR WARTTINGER, of Berlin, Kingdom of Prussia, Empire of Germany, have invented certain new and useful 5 Improvements in Portable Dumping Apparatus, (which have heretofore been patented in the following countries: By the government of Germany, No. 38,613, dated December 2, 1886; France, No. 175,189, July 30, 1886; Great Britain, No. 4,298, March 26, 1886; Belgium, No. 72,558, April 15, 1886; Austria-Hungary, No. 12,614 and No. 38,472, August 12, 1886; Italy, 10 19,766/148, of May 4, 1886; Spain, No. 8,930, July 26, 1886,) of which the following is a 15 specification.

The object of my invention is to provide a new and improved portable apparatus, which is to be used for unloading sand, coal, and otherlike material from scows, vessels, trenches, 20 excavations, &c., into other vessels or wagons or to deposit them on suitable dumps.

The invention consists in the construction and combination of various parts and details, as will be fully described and set forth here- 25 inafter, and pointed out in the claims.

In the accompanying drawings, Figure 1 represents a side view of my improved portable dumping apparatus, showing the same on a scow, and used for unloading material from 30 a scow or vessel and loading it into a wagon, parts being broken out and others being in section. Fig. 2 is a front view of the same, parts of the scow being broken out and others in section. Fig. 3 is a side view of my im- 35 proved portable dumping apparatus as constructed for use on land, parts being broken out and others being in section. Fig. 4 is a plan view of the same, parts being broken out and others in section. Fig. 5 is an end view of the 40 same, parts being in section. Fig. 6 is a side view of the same folded for transportation. Fig. 7 is an enlarged detail sectional view of the upper part of the apparatus; and Fig. 8 is a sectional view of part of the track, showing 45 part of a vertical track connected with the inclined track.

Similar letters of reference indicate corresponding parts.

The apparatus to be used on land and the 50 apparatus to be used on a float or scow are es-

sentially the same, there being only differences in construction required by the different uses of the apparatus.

Referring to Figs. 3, 4, 5, 6, and 7, *h* is the inclined track-frame, which is pivoted at its 55 upper end to the upper end of the inclined frame *g*, the upper end of which rests on a cross-piece uniting two standards, *c c*, hinged at their lower ends to the side base-beams, *b*, secured to and resting on the base cross-pieces 60 *a*. At or near the middle of their length the inclined bars *g* rest on a cross-piece, *g'*, uniting the two bars *e*, which are hinged to the standards *c*, and are supported at their opposite ends by the braces *f*, the lower ends of which 65 are rested against suitable shoes, *f'*, on the top edges of the side base-beams, *b*, near those ends of the said base-pieces *b* opposite those to which the standards *c* are pivoted. At the highest point of the bars *g*—that is, at the end 70 at which the tracks *h* are pivoted to the same—an inclined part, *i*, is formed, which is inclined in the opposite direction of the inclined bars *g*, and at the lower end of which inclined part *i* the upwardly-projecting arms *i'* are formed, 75 in the upper ends of which the rollers *i''* are pivoted.

The lower end parts of the tracks *h* may rest on the bars *g*, or may be supported by a rope, *w*, secured to a cross-piece, *n*, fastened to the lower 80 end of the tracks, which rope is passed over a pulley, *m*, pivoted in the upper end of a standard, *o*, having its lower end pivoted on the base-block *p*, placed on the ground adjacent to the rear cross-piece, *a*.

If desired, two ropes *w* may be used for each track, or, in case two tracks are used, one may be used for each track, and the two standards *o* may also be united by a cross-piece. The ropes *w* are secured to winding-drums *s*, 90 provided at the ends with handles *l* for turning them. The inclined track *h* may be extended by hanging track-sections on the same, as shown in Fig. 3.

On a transverse shaft, *W'*, journaled in the 95 bars *e*, the wheels *W''* are rigidly mounted, which wheels serve as fly-wheels when the apparatus is erected, or as transporting-wheels when the apparatus is being transported, as shown in Fig. 5. A driving-chain, *V'*, is 100

passed over a sprocket-wheel, V^2 , located on one end of the shaft, and over a sprocket-wheel, V^3 , on a transverse shaft, D' , journaled in the side pieces, e , and provided with crank-arms 5 D at the ends. If desired, said sprocket-wheel and chain may be provided at each side of the apparatus.

In place of using chains and sprocket-wheels, the shaft w' can be driven from the 10 shaft D' by means of the cog-wheels.

The hoisting-ropes B , which are passed over pulleys t on the upper end of the frame, are secured to winding-drums A , mounted loosely 15 on the shaft W' , and provided with clutching-disks A' , which can be engaged with clutching-disks A^2 , mounted on the shaft W' , and in such a manner as to turn with the same and move on the same in the direction of its length. The clutching-disks A^2 can be shifted on the 20 shaft W' toward or from the clutching-disks A' by means of levers C , pivoted to the frame, and said levers can be locked in place by latches w' , Fig. 5, pivoted on the frame of the machine. Below said latches the wedge-shaped 25 parts w^2 are provided, which are suspended by chains w^3 from arms w^4 , projecting from a shaft, z , journaled in the upper part of the frame, which shaft z has arms y , projecting upward at the side of the tracks, and provided 30 with notches y^2 at the upper ends, adapted to receive cross-rods y' , uniting frames y^3 , projecting downward from the bottom of the car-body y^4 , which is mounted to swing on the frontaxle of the truck of the car. The chains w^3 35 are also connected with foot-levers E , and said foot-levers are connected by chains E' , passed over suitable pulleys, E^2 , with brake-bands E^4 , resting and pressed by suitable springs against the brake-wheels E^5 on the ends of the 40 rope-drums A . When the fly-wheels W^2 are turned in the direction of the arrow, Fig. 3, by means of the crank-arms D or other devices, the ropes B are wound upon the drums and raise the car-truck until it arrives at the highest 45 part of the inclined track, when it runs down the inclined part i , the cross-rod y' of the car-body passing into the notches y^2 , Fig. 7, of the arms y , and swinging said arms in the direction of the arrow, Fig. 7, whereby the 50 arms y are raised and the rear end of the car raised also, so as to automatically dump its load, as shown in Fig. 3. At the same time that the arms y are swung up in the direction of the arrow, Fig. 7, the arm w^4 is raised, 55 whereby the chain w^3 is pulled upward, and the wedge-shaped part w^2 , striking against a latch, w' , raises the same, whereby the corresponding lever C is released, and by suitable springs acting on it is thrown in such a manner as to disengage the clutching-disk A^2 from the clutching-disk A' , whereby the further winding of the rope B is prevented. Before the cars are hoisted, the levers C must be shifted in such a manner as to engage the clutch-disks A^2 60 with the clutch-disk A , the levers being held in place by the latches w' . When the car is emptied, and is to be removed from the inclined

part i of the track, one of the foot-levers E is forced down, whereby the arm w^4 of the shaft z is swung down, and the arms y are swung in an 70 inverse direction to the arrow, Fig. 7, whereby the car is moved up the inclined part i , and the rear part of the car-body is swung down on its truck. By pressing down the said foot-lever E the spring brake-band E^4 is disengaged 75 from its brake-wheel E^5 , thus permitting the car to run down the incline and to uncoil the rope B from the winding-drum. The uncoiling of the rope from the winding-drum can be stopped by releasing the spring-brake, to permit the same to act on the brake-wheel. When another loaded car is to be raised, a lever, C , must be shifted, so as to engage its clutching-disk A^2 with the clutching-disk A' 80 on the winding-drum A . 85

When the apparatus is erected for use, as shown in Fig. 3, the fly-wheels W^2 are a short distance above the ground and can revolve freely. When the apparatus is to be adjusted for transportation, the pivots of the tracks h 90 and the braces f are removed, and the braces d' , which brace the central standard, c' , as shown in Fig. 5, and are held to the same by pins, are disconnected. The standards c are swung to the front, whereby the base b is raised, 95 the rear part of the base being held in raised position by means of the rope w , which is tied to the base of the machine. The entire machine is thrown forward into the position shown in Fig. 6, the wheels W^2 resting on the 100 ground.

When the apparatus is to be erected for use the above steps are reversed, and the parts united.

The arms y rest against a movable cross-piece, x , which can be shifted by means of the screw x' , passed through the fixed cross-piece x^2 . The cross-piece x can thus be adjusted to permit the arms y to swing down more or less, whereby the arms y can be so adjusted that 110 their notched upper ends will be the same distance above the tracks as the rods y' .

In the construction shown in Figs. 1 and 2 the apparatus is mounted on a flatboat or scow, and in this case the track-bars are supported 115 by a frame, B^2 , which in turn is supported by ropes B^4 , passed over suitable pulleys on the top of the upright supporting-frame on the scow or boat B^5 .

To hold the boat steady, piles C^2 are passed 120 through openings in the same, said piles being provided with racks, with which suitable pinions on the scow engage, a gear mechanism being provided for revolving said pinions, whereby the piles can be forced downward into 125 the bottom of the river or harbor, as shown in Fig. 2, and thus the scow is held in place. The inclined track may be provided at its upper end with an extension for extending over a roadway, as shown in Fig. 1. The lower 130 part of the inclined track is passed into a vessel moored alongside of the scow, from which vessel the load is to be discharged.

A counting mechanism, D^3 , is provided on

the track, and has an upwardly-projecting arm operated by the cars, by means of which the number of car-loads taken over the track is counted.

5 In case the cars are to be drawn up a vertical embankment, the lower part of the track is connected with a vertical track, P³. (Shown in Fig. 8.) The mechanism for dumping the car shown in Figs. 1 and 2 is the same as that 10 shown in Figs. 3, 4, 5, and 7.

The subject-matter covered by the claims of my application, Serial No. 198,920, filed April 15, 1886, is herewith disclaimed in this application.

15 Having thus described my invention, I claim as new and desire to secure by Letters Patent—

1. In an automatic dumping apparatus, the combination, with an inclined frame, of a track pivoted to the same at the highest point of the 20 frame, which frame is provided with an inclined part at the highest point, said part being inclined in the opposite direction to the track, and the lower part of the track being supported by a rope passed over a suitable pulley 25 on a standard and secured to a winding-drum, substantially as shown and described.

2. The combination, with an inclined track provided at its upper end with a part inclined in the opposite direction to the track, of a 30 rocking shaft at the highest point of the inclined track, and notched arms projecting from said rocking shaft upward at the sides of the track, substantially as shown and described.

3. In an automatic dumping apparatus, the 35 combination, with an inclined track provided at its highest point with a part inclined in the opposite direction to the track, of a rocking shaft at the highest point of the track, notched arms projecting from said rocking shaft upward at the sides of the track, an arm projecting from the rocking shaft, and a chain secured to said arm, substantially as shown and described.

4. In an automatic dumping apparatus, the 45 combination, with an inclined track provided at its highest point with a part inclined in the opposite direction to the track, of a rocking shaft at the highest point of the track, notched arms projecting from said shaft at the sides of 50 the track, an arm on said rocking shaft, a chain or rope extending downward from said arm, and a foot-lever connected with said rope, substantially as shown and described.

5. In an automatic dumping apparatus, the 55 combination, with an inclined track provided at its highest point with a part inclined in opposite direction to the track, of a rocking shaft at the highest point of the track-frame, notched

arms secured to said shaft and projecting upward at the sides of the track, an arm on said 60 rocking shaft, and an adjustable cross-piece against which said notched arms can rest when in the lowered position, substantially as shown and described.

6. In an automatic dumping apparatus, the 65 combination, with an inclined track, of a rocking shaft at the highest point of the same, notched arms on said shaft, an arm projecting from the rock-shaft and connected with a rope or chain, a winding-drum mounted loosely on 70 a shaft on the track-frame, a clutch device on the drum, a clutch device on the shaft, levers for shifting the clutch device on the shaft, latches for locking said levers in place, and of wedge-shaped parts, the wedge-shaped parts 75 being provided below the latches for locking the clutch-levers in place, substantially as shown and described.

7. In an automatic dumping apparatus, the 80 combination, with an inclined track, of a rocking shaft at the highest point of the same, notched arms projecting from the rocking shaft, an arm projecting from the rocking shaft, a winding-drum, clutch devices on the winding-drum and on the shaft of the same, 85 levers for operating the clutch devices on the shaft, latches for locking said levers in place, a wedge-shaped piece secured to a chain fastened to the arm of the rock-shaft, latches for locking the clutch-levers in place, a spring 90 brake-lever connected with a foot-lever by a chain or rope, and a rope or chain connecting said lever with the wedge-shaped piece, substantially as shown and described.

8. The combination, with an inclined frame, 95 of a track pivoted on the same, uprights supporting the inclined frame and pivoted to a base, side pieces pivoted to the uprights, in which side pieces the winding-shaft is mounted, and braces supporting the side pieces in which 100 the winding-shaft is mounted, substantially as shown and described.

9. In a dumping apparatus, the combination, with an inclined track, of the rocking shaft z, the notched arms y on the same, the adjustable cross-piece x, the screw x', and the fixed cross-piece x², substantially as shown and described.

In testimony that I claim the foregoing as my invention I have signed my name in presence of two witnesses.

GOTTLOB WARTTINGER.
